UNITED STATES PATENT OFFICE.

JOSEPH B. FLEENOR, OF SEATTLE, WASHINGTON.

WRENCH.

1,361,237.

Specification of Letters Patent.

Patented Dec. 7, 1920.

Application filed April 19, 1920. Serial No. 374,956.

To all whom it may concern:

Be it known that I, JOSEPH B. FLEENOR, a citizen of the United States, and residing at Seattle, in the county of King and State of

5 Washington, have invented certain new and useful Improvements in Wrenches, of which the following is a specification.

This invention relates to an improvement in wrenches, and is particularly directed to 10 a means whereby the wrench may be rapidly and easily adjusted to accommodate different size objects.

The improved wrench is constructed to 15 permit a manual adjustment of the movable jaw with respect to the fixed jaw, through arranging such movable jaw in any one of a series of notches carried by the fixed jaw, the construction insuring a maintenance of the adjusted position in the use of the 20 wrench as such.

In the drawings:—

Figure 1 is a perspective view of my improved wrench.

Fig. 2 is a view in elevation showing the 25 parts of the wrench in one adjusted position for use.

Fig. 3 is a similar view showing the movable jaw in a position permitting its adjustment relative to the fixed jaw.

30 Fig. 4 is an edge view of the wrench.

The improved wrench comprises a fixed jaw 1, here shown as with a rounded jaw proper 2 serrated or roughened on the inner surface at 3. The outer edge of the handle 35 portion of this jaw 1 is formed in a series of spaced notches 4, these notches having the upper wall 5 at a materially great angle to the longitudinal plane of the jaw than the lower wall 6. The movable jaw 7 having the 40 rounded serrated jaw proper 8 has a straight portion 9 formed with the recess 10 in which the handle portion of the jaw 1 is slidable. The outer edge of the recess or opening 10 is formed with a projection or tooth 11 45 adapted to snugly fit any one of the recesses 4. The opposite wall 12 of the opening 10 is inclined with respect to the longitudinal plane of the jaw 7, the inclination being such that when such wall or edge 12 is in 50 contact with the fixed jaw 1 the tooth 11 is beyond the recesses of the jaw 1.

A keeper is arranged to overlie the tooth end of the jaw 7, such keeper comprising a bar 13 having inwardly extending arms 14, 55 which engage the respective side surfaces of the jaw 1, and are movably connected thereto

by pin and slot connection 15. Springs 16 secured to the jaw 1 and to pins 17 at the respective ends of the keeper, serve to hold such keeper at the inner limit of movement. 60

As will be noted from Fig. 1 of the drawings that end of the jaw 7 remote from the jaw proper thereof will when the tooth 11 engages a particular notch 4 be in parallelism with the keeper bar 13, so that in this 65 position said keeper bar under the tension of the springs 16 serve to hold the movable jaw in the particular notch for the wrench operation. When it is desired to adjust the movable jaw to a new position, it is 70 turned until the wall 12 of the opening 10 is forced into contact with the adjacent edge of the handle portion of the jaw 1. This action is of course against the tension of the springs 16, and forces the keeper outwardly, 75 at the same time forcing the tooth 11 from the particular notch. The edge 12 now operates as a sliding base on which the movable jaw may be moved to the new position, and released. The keeper then acts to force the 80 movable jaw to a position to cause proper coaction between the tooth 11 and the selected notch.

It is of course apparent that with the 85 movable jaw held by the notch and tooth engagement, the wrench is adapted to be used as any ordinary wrench, while at the same time the adaptability of the adjustment permits a wide range of normal spacing between the jaws proper, and hence a 90 highly desirable utility of wrench structure.

What I claim is:

1. A wrench comprising a fixed jaw, formed with notches, a sliding jaw having a tooth to engage any one of said notches, 95 a keeper adapted to bear squarely against the end of the movable jaw when the tooth is in its notch, and spring means for holding the keeper in operative position.

2. A wrench comprising a fixed jaw 100 formed with notches, a sliding jaw having a tooth to engage any one of said notches, a keeper movably mounted on the fixed jaw and adapted to engage the end of the movable jaw when in operative position, and 105 spring means for normally holding the keeper in operative position.

3. A wrench comprising a fixed jaw formed with notches, a sliding jaw having a tooth adapted to engage any one of said 110 notches, a keeper formed of a bar having lateral extensions from the ends thereof

slidably engaging the fixed jaw, the bar of the keeper being adapted to engage the end of the sliding jaw when in operative position, and springs for normally holding the keeper in operative position.

4. A wrench comprising a fixed jaw formed with notches, a sliding jaw having a tooth adapted to engage any one of said notches, a keeper for engaging the end of

the sliding jaw when in operative position, 10 said keeper being formed of a U-shaped bar having the ends slidably engaged with the fixed jaw, and springs having the ends secured to the keeper and fixed jaw for normally holding the keeper in operative position. 15

In testimony whereof I affix my signature.
JOSEPH B. FLEENOR.
